UNITED STATES PATENT OFFICE

1,996,399

SEWING MACHINE

Arthur Bates, Leicester, England, assignor to
United Shoe Machinery Corporation, Paterson,
N. J., a corporation of New Jersey

Original application July 8, 1927, Serial No.
204,278. Divided and this application November
26, 1932, Serial No. 644,444. In Great
Britain July 20, 1926

4 Claims. (Cl. 112—60)

This invention relates to sewing machines for use in the manufacture of boots or shoes and is particularly concerned with curved needle machines for stitching together the sole and upper 5 of turn shoes. It has especially in view the improvement of that class of machine which is used to sew turn slippers without previous lasting and is described in patent to Richards No. 1,163,558, dated December 7, 1915, and in patent to Bates 10 No. 1,188,388 and to Bates and Richards No. 1,188,389, dated June 27, 1916.

The present invention has for its objects to provide a machine of this class of simple and light construction as a whole and to provide improved 15 forms of sewing and work feeding devices of machines of this class to adapt the same for running at comparatively high speed and render the same well capable of operating upon material of inferior quality without damaging the material (for 20 instance by pulling the stitches through the material as is liable to occur with the heavy machines today in use) while also capable of sewing material of good quality in as satisfactory a manner as with machines heretofore in use.

Such slipper turn shoes as referred to above 25 may require to have sewn to the upper by the sewn seam either a felt or rubber sole, or a combination sole of felt or rubber and leather, or a sole composed only of leather.

Other objects and the various novel features of 30 the invention will become apparent to those skilled in the art from the following description given by way of example of one form of machine according to the invention and embodying its 35 various features in particular forms thereof. The said form of machine has sewing instrumentalities of the nature and functioning in the same general way to sew a chain stitch seam in work on a horn as the machines in customary use for slipper 40 turn shoe sewing and the original forms of which machine is described in the earliest dated of the aforementioned patents.

In the accompanying drawing, Fig. 1 is a view 45 in side elevation of the machine and Fig. 2 is a detail view illustrating the relative arrangement of the work supporting horn, the needle, the pres- 50 er, the back rest and the feed point.

The novel machine comprises a base 1, adapted 55 to be fixed to a work bench or pedestal, which base has clamped in it so as to be adjustable vertically a vertical stem formed on a frame, to the upper face of which is bolted a machine head 2.

The head has on it spaced uprights respectively 55 carrying two bearings in which is rotatably mounted a horizontal driving or cam shaft 3 ex-

tending across the machine. The driving shaft has rotatably mounted on it at its right hand end a driving pulley 4 which is adapted to be clutched to the shaft by a clutch of the type illustrated and described in the patent to Jerram No. 1,124,620, dated January 12, 1915. On the opposite end of the shaft is a hand wheel by which the driving shaft may be rotated. The clutch is enclosed in a substantially cylindrical casing extending from the right-hand upright of the head 10 and a rod 6 passes from the clutch to a treadle for controlling the clutch. Between the clutch and hand-wheel the head encloses a number of cams and eccentrics which operate the sewing and feeding devices of the machine.

The frame carries a rotatable horn 7 on which the work is supported during the sewing and the horn is substantially of the shape and disposition of, and is controlled in a similar manner to that shown in Patent No. 1,188,388, above referred to. A curved hook needle 8 is fixed in an arm 9 which projects from a horizontal stud or spindle extending across the frame and rotatably mounted at the front of the head. The arm has pivotally connected to it one end of a rearwardly extending curved link 10, the other end of which is pivotally connected to the front end of a needle-actuating arm 11 which extends back under the cam shaft to a point behind and below the latter where it is pivoted on a shaft 12, extending across the machine, rotatably mounted at the rear of the head. The needle-actuating arm has pivotally connected to it between its pivot and its connection to the link the lower end of a cam link 13, the upper end 30 of which has formed on it a rectangular strap 14 surrounding a four-way cam on the cam shaft. Pivotally mounted on the head concentrically with the needle is a needle guard 15 of usual construction and actuated by the needle arm as 35 usual. For a complete description of the machine, reference may be had to the inventor's pending application Serial No. 204,278, filed July 8, 1927 of which the present application is a division and upon which Patent No. 1,911,050 is 40 sued May 23, 1933.

A tubular looper 16 having an offset thread delivery end is mounted to rotate about its axis in an arm 17 secured within the frame. A thread finger 230 operating in the usual way is 50 fixed, inside of the head, on the end of a horizontal shaft extending across the machine and rotatably mounted in a bearing on the head.

When operating upon shoes having a combination leather and felt sole, the shoe is fed over 55

the horn tip through the machine by a feed point which digs into the upper and the felt of the sole inside the line of the seam. The feed point indicated at 23 is fixed in the lower end of a vertical bar 24 slidingly mounted in a vertical bearing which is formed on the forward end of a horizontal, rearwardly extending feed lever 25 pivoted about mid-way of its length on a vertical pivot 26 fixed in the head under the cam shaft. The feed point is actuated in proper timed relation to the movements of the other stitch forming devices from the cams on the cam shaft 3, as more fully described in the inventor's pending application above referred to.

In the embodiment of the present invention a presser or bender 35 is pivoted on an eccentric portion of a horizontal stud 36 fixed in the head to extend from right to left so that by rotating 20 the stud the heightwise and forward or rearward position of the presser may be adjusted. The presser is forked so as to engage the work at each side of the needle and bends down the edge of the shoe so as to position and hold it 25 on the horn tip while the needle enters the work and the presser holds the work while the needle is retracted.

The presser has a depending arm to which is pivotally connected the forward end of a rearwardly extending rod 37 passing under the cam shaft, the rear end of which slides through a pin 38 rotatably mounted in a downwardly extending arm of the lever 11. The rod has on its rear end a nut between which and the rear side 35 of the pin 38 is a spring 39 surrounding the rod which yields after the presser engages the work.

The other stitch forming and thread handling devices including a take-up lever 40 and an auxiliary take-up 41 are the same as described in the application referred to.

When operating upon combination felt and leather soles, a back gage 51 is provided. A portion of the work engaging face of the back gage is curved forward so as to bend down the work as it moves past it into the path of the presser.

The construction and arrangement described is one that results in the machine having most of its mechanism in a comparatively restricted space generally speaking beneath the level of 50 the cam shaft and behind a vertical plane parallel to the cam shaft and through the point of operation on the shoe. Thus save for the auxiliary take-up and the front arm of the main take-up lever, none of the thread and work 55 handling parts of the machine or the link, lever or like mechanism connecting the same with the cams or the like on the cam shaft lie above a plane containing the cam shaft axis and extending upwardly and rearwardly at some 20° 60 only to the horizontal. Again, none of such parts except the looper itself and the roll of the main take-up extend substantially forward of a vertical plane parallel to the cam shaft and passing through the horn tip.

65 The following particulars of the relative timing of the parts will further indicate the nature of the movements:

The machine has a definite stopping point which will be considered as the zero position. The 70 needle is then fully retracted and stays so until the cam shaft has turned 65° when it advances to reach forward position 105° later staying forward then during 55° of cam shaft rotation when it commences to move back and reaches its fully 75 retracted position 25° before the cam shaft rota-

tion is completed in which position it then stays. The looper occupies 45° of cam shaft rotation and 5 290° of its own rotation in laying the thread fully round the needle from the time it first brings the thread in contact with the side of the needle which occurs after the needle has remained fully advanced for 20° of cam shaft rotation and after the looper has itself moved some 160° from its starting position. The thread finger is forward until the cam shaft has rotated 135° when it retires during 35° to stay back during 90° and then advances during 45° to stay forward for the remainder of the cycle. The feed movement occupies 55° of cam shaft rotation of which the first five degrees actually occur during the last 15 five degrees of cam shaft rotation to the zero position above adopted. The feed member stays in its left hand extreme and in its depressed positions until the cam shaft has turned 185° from the zero position when the needle is fully advanced. Then during 5° of cam shaft rotation the feed member lifts and thereafter returns during 40° of cam shaft rotation to its starting position where it dwells, lifted, during 70° of cam shaft rotation to then fall during 10° and thereafter 25 dwell in that position for 45°. The main take-up occupies 180° in rising and 180° in falling reaching its fully lifted position (i. e. the end of its pulling movement) at about 180° from said zero. The presser is in raised position at the 30 beginning of the cycle for 50° when during 20° it falls to engage the work before the needle enters it and then stays down during 165° of cam shaft rotation when after the cam shaft has rotated 235° from zero position it commences to lift 35 to reach its fully raised position just at the end of the cycle.

Having thus described the invention, what is claimed is:

1. A sewing machine having, in combination, 40 a horn arranged to extend within and support a shoe, stitch forming devices including a curved needle arranged to pass through the work in a path substantially parallel to the work engaging surface of the horn, a presser arranged to 45 press the upper against the shoe sole and hold the work on the horn during the passage of the needle, and a back gage arranged to bear on the shoe adjacent the presser and shaped to bend the upper into a position to be engaged by the 50 presser.

2. A sewing machine having, in combination, 55 a horn arranged to extend within and support a shoe, stitch-forming devices including a curved hook needle arranged to pass through the work in a path substantially parallel to the work engaging surface of the horn, a work engaging member acting on the work inside the line of the seam to feed the work, and a presser engaging the work along the edge of the sole to hold it on the horn 60 during passage of the needle.

3. A sewing machine having, in combination, 65 a horn arranged to extend within and support a shoe, stitch-forming devices including a curved hook needle arranged to pass through the work in a path substantially parallel to the work engaging surface of the horn, a work engaging member acting on the work inside the line of the seam to feed the work, a presser engaging the work along the edge of the sole to hold it on the horn, 70 means for actuating the needle, and a connection from the needle actuating means to the presser for causing the presser to bend the upper and edge of the sole over the horn tip while the needle enters the work.

4. A sewing machine having, in combination, a horn arranged to extend within and support a shoe, stitch-forming devices including a curved hook needle arranged to pass through the work in a path substantially parallel to the work engaging surface of the horn, a work engaging mem- ber acting on the work inside the line of the seam to feed the work, and a presser engaging the work along the edge of the sole to bend down the edge and position it on the horn tip for the passage of the needle.
